UNITED STATES PATENT OFFICE.

ANTOINE THEODORE LORME, OF WEST HOBOKEN, NEW JERSEY.

EXPANSIBLE NUT AND BOLT.

SPECIFICATION forming part of Letters Patent No. 349,851, dated September 28, 1886.

Application filed June 18, 1886. Serial No. 205,306. (No model.)

To all whom it may concern:

Be it known that I, ANTOINE THEODORE LORME, of West Hoboken, in the county of Hudson and State of New Jersey, have invented certain new and useful Improvements in Wedge-Nuts, of which the following is a specification.

This invention relates to an improved wedge-bolt for attaching signs, sign-plates, and other articles to stone in a reliable manner; and the invention consists of a screw-bolt having a threaded and conically-tapering shank, and of wedge-shaped jaws that are provided with serrations at their outer surfaces, and with threaded inner faces, said wedge-jaws being forced outwardly in the socket-hole of the stone by the tapering shank of the screw-bolt, so as to rigidly support the sign-plates or other articles.

In the accompanying drawings, Figure 1 represents a horizontal section showing my improved wedge-bolt respectively in section and top view. Fig. 2 is a vertical transverse section of the same on line $x-x$, Fig. 1, drawn on a larger scale; and Fig. 3 is a horizontal section of my improved wedge-bolt arranged to support two plates.

Similar letters of reference indicate corresponding parts.

Referring to the drawings, A represents a screw-bolt that is provided with an enlarged and nicked head, a , and a shank, b , having a tapering and screw-threaded end, b' . The screw-bolt A is retained in the socket-holes d of the stone by means of two or more wedge-shaped jaws, B B, which are provided at their outer surfaces with rows of serrated teeth d , that are inclined in forward direction toward the head of the screw-bolt A. The inner surfaces of the jaws B B are made wedge shaped, so as to correspond to the inclination of the tapering end b' of the screw-bolt A, and screw-threaded, so as to be engaged by the threaded tapering end b' .

For attaching the sign-plate C in position,

the bolt is passed through the holes of the plate and the wedge-jaws applied, by a thin thread or otherwise, to the hind part of the tapering end b' of the bolt A, so that their diameter is less than the diameter of the socket-hole d . When the sign-plate C and bolts A are in position on the stone, the screw-bolts A are turned, which causes the wedge-jaws B B to advance on the screw-threaded ends b' , so that they are forced in outward direction until they bite rigidly in the side walls of the sockets d , as shown in Fig. 1.

When a sign, letter, or other piece, C', is to be supported in addition to the sign-plate, the arrangement shown in Fig. 3 is used. In this case the shank b of the screw-bolt A is nicked and screw-threaded at its front end, and a nicked and tapering nut, a' , used in place of the head a , which nut is screwed home into the countersunk hole of the sign-plate C, while a second screw-nut, a'' , is screwed on the outer end of the shank, so as to retain the sign, letter, or piece C'. In this manner a wedge-bolt for sign-plates or other articles is obtained that can be attached to stones of all kinds without the use of lead filling or other device, and detached whenever required by simply unscrewing the screw-bolts and removing them, together with the wedge-jaws, from the socket-holes of the stone.

Having thus described my invention, I claim as new and desire to secure by Letters Patent—

The combination of a screw-bolt having a nicked head and a shank with a tapering and screw-threaded end, and wedge-jaws having exterior rows of serrations and interior threaded faces that fit on the tapering end of the shank, substantially as set forth.

In testimony that I claim the foregoing as my invention I have signed my name in presence of two subscribing witnesses.

ANTOINE THEODORE LORME.

Witnesses.
